UNITED STATES PATENT OFFICE.

MAXIMILIAN TOCH, OF NEW YORK, N. Y., ASSIGNOR OF ONE-HALF TO HENRY M. TOCH,
OF NEW YORK, N. Y.

BOTTLE FOR ADVERTISING.

1,009,453.

Specification of Letters Patent. Patented Nov. 21, 1911.

Application filed July 8, 1911. Serial No. 637,499.

To all whom it may concern:

Be it known that I, MAXIMILIAN TOCH, a citizen of the United States, residing at 329 West Eighty-sixth street, New York, in the county of New York and State of New York, have invented certain new and useful Improvements in Bottles for Advertising, of which the following is a specification.

My invention relates to a device primarily intended for use as a means for advertising or exhibiting the properties of water-proofed concrete.

Referring to the drawing, A is a glass bottle from which the bottom portion has been removed; B is a cork; and C is a filling or plug of concrete. The concrete may be made of any suitable mixture of sand and cement, such as the usual 3 to 1 mixture of these materials, and is, preferably, water-
proofed in any known way, such as, for example, by the process described in U. S. Patent No. 976,520, patented November 22, 1910.

The plug of concrete may be put into place, after the bottom portion of the bot-

tle has been removed, by corking the upper 25 end, filling the bottle with sand to the zone at which the concrete plug is desired, pouring in the concrete mixture to the desired thickness and ramming it down. When the concrete plug has set, the bottle is uncorked 30 and the sand removed. The bottle can then have liquid poured into it and will afford a striking ocular demonstration as to the permeability of the concrete to the liquid in the bottle. 35

What I claim is:

A glass receptacle comprising a hollow body open at its upper and lower ends and a smooth plug of waterproofed concrete cast into and irremovably attached to the lower 40 portion of said body.

In testimony whereof, I affix my signature in presence of two witnesses.

MAXIMILIAN TOCH.
